RAIL CAR BODY

George J. Adams, Santa Monica, and Harry L. Warner,
West Covina, Calif., assignors to Stanray Corporation,
Chicago, Ill., a corporation of Delaware

Filed July 30, 1969, Ser. No. 18,472

Term of patent 14 years

Int. Cl. D12—03

U.S. Cl. D66—1

FIG. 1 is a perspective view of a rail car body showing our new design, as viewed from one side and below; and FIG. 2 is another perspective view showing our design, as viewed from the opposite side and above.

The broken line showings in FIGS. 1 and 2 are only to illustrate an environment in which our design may be used, and do not form parts of our design itself.

We claim:

The ornamental design for a rail car body, substantially as shown and described.
